Primary Examiner — Sheryl Lane*Assistant Examiner* — Samantha Wood(74) *Attorney, Agent, or Firm* — Sughrue Mion, PLLC(57) **CLAIM**

The ornamental design for a mute, as shown and described.

DESCRIPTION

FIG. 1 is a perspective view of the front, top and right side of a mute showing my new design;

FIG. 2 is a perspective view of the front, bottom and right side thereof;

FIG. 3 is a front view thereof;

FIG. 4 is a right side view thereof;

FIG. 5 is a top plan view thereof; and,

FIG. 6 is a bottom view thereof.

The broken line showing the mute is included for the purpose of illustrating portions of the mute and forms no part of the claimed design.

1 Claim, 6 Drawing Sheets(56)
